UNITED STATES PATENT OFFICE.

FRANK A. FANUCCI, OF SCRANTON, PENNSYLVANIA.

FIGURE TOY.

Application filed October 26, 1923. Serial No. 670,900.

To all whom it may concern:

Be it known that I, FRANK A. FANUCCI, citizen of the United States, residing at Scranton, in the county of Lackawanna and State of Pennsylvania, have invented certain new and useful Improvements in Figure Toys, of which the following is a specification.

This invention relates to toys and has more particular reference to a toy of the figure type, the same comprising a figure of a well-known comedian, that is resiliently connected at its opposite ends to a supporting means whereby said figure may be made to jump up and down or rotate quickly in a reverse direction after the same has been rotated by hand in the opposite direction.

An additional object of this invention is to provide a toy wherein the figure element includes a body portion in the form of a balloon that has painted thereon the figuration of the figure's arms together with the clothing carried by the body portion, it being obvious that this balloon may be blown up to such a degree for giving the appearance to the figure of having a relatively large stomach which will prove highly amusing to small children.

An additional object of the invention is to provide an article of the above character that may be manufactured and marketed at an extremely small cost.

With the above and other objects in view as the nature of the invention will be readily understood, the same comprises the novel form, combination and arrangement of parts hereinafter more fully described, shown in the accompanying drawing, and claimed.

In the drawing, wherein there is shown the most preferred embodiments of the above invention with which I am at this time familiar, the figure is a perspective of a toy constructed in accordance with this invention.

Now having particular reference to the drawing my novel toy comprises a supporting element designated generally 5, and a figure element designated generally 6, resiliently connected at its upper and lower ends to the upper and lower ends of said supporting element through the medium of rubber or other suitable elastic bands 7, whereby the figure is supported intermediate the upper and lower ends of said stand or support 5, which, in view of the resilient

connections 7 will allow the figure 6 to be so agitated as to give the appearance of the same dancing or hopping about. Also, a rotation of the figure in one direction by hand will wind up the element 7, whereupon a release of the figure will cause its quick rotation in an opposite direction, also for affording a high degree of amusement to children.

The stand or supporting member 5 comprises a single length of steel wire, so bent upon itself as to provide a relatively long upright curved portion 8 that terminates at its upper end into an inwardly bent portion 9 that affords a means for securing the uppermost elastic connection 7 to the stand.

The opposite end of said single length of wire is so bent as to provide a relatively large circular or ring like member 10 and an inwardly extending arm 11 that is so bent as to position above the table or other support upon which the toy is placed, and to which the lowermost elastic connection 7 is secured.

It will thus be seen that the circular or ring like portion 10 affords a means whereby the toy may be set in an upright position upon the table or other support.

The figure element 6 of the invention comprises three separate members, a lower limb member 12, a body member 13, and an integral head and neck member 14.

The lower limb member 12 is preferably of a celluloid material molded to simulate a man's trousers and shoes in wearing relation to each other. Within the upper end of this member 12 is adapted to be positioned and adhesively secured the body member 13, which is in the form of a rubber balloon, upon which is painted the arms of the figure together with the different clothing worn by that portion of the body.

The integral neck and head portion of said figure element is preferably of celluloid molded into the design shown, the same being hollow for allowing the neck portion of said balloon to pass therethrough after which the balloon may be inflated to the desired degree and then tied by the uppermost elastic connection 7.

It will thus be seen that I have provided a highly novel and efficient form of toy of the figure jumping variety, one that may be manufactured and marketed at a small cost.

Minor changes may be made in the invention without departing from the spirit and scope of the appended claims.

Having thus described my invention, what I claim as new and desire to secure by Letters Patent is:

10. 1. In a figure toy, a molded lower limb simulating element, an inflatable body element having a neck portion on one end, said inflatable body element being adapted for connection with said lower limb element, and a hollow head and neck element through which is adapted for extension the neck portion of said inflatable body element.
15. 2. A figure toy comprising a hollow molded part having an external shape simulating a man's trousers and shoes in wearing relation, said part being open at its upper end, an elastic balloon inflated to form the body of the figure, the surface of said balloon being painted to represent
- 20.

clothing covering the body, said balloon fitting into the upper open end of the molded portion and attached thereto, and a hollow element shaped to simulate a person's head and neck, the air intake of said balloon passing through said last named element to maintain it in place.

25. 3. A support for a toy of the class described formed from a single length of wire having its upper end directed laterally in a horizontal direction, the upper and intermediate portions of the wire being bent to form a vertical standard, the opposite end portion of the wire being bent to form a ring-like base, and the extremity of the last named portion of the wire being directed into said ring-like portion to provide a lower attaching arm.

30. 35. In testimony whereof I affix my signature.

FRANK A. FANUCCI.
